(57) **CLAIM**

The ornamental design for a varus/valgus resection guide set, as shown and described.

DESCRIPTION

FIG. 1 is a perspective view of the valgus guide of the varus/valgus resection guide set of our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear end elevation view thereof; and

FIG. 7 is a front end elevation thereof.

FIG. 8 is a perspective view of the varus guide of the varus/valgus resection guide set of our new design;

FIG. 9 is a top plan view thereof;

FIG. 10 is a bottom plan view thereof;

FIG. 11 is a left side elevation view thereof;

FIG. 12 is a right side elevation view thereof;

FIG. 13 is a rear end elevation view thereof; and,

FIG. 14 is a front end elevation thereof.

The broken line showing of holes and surface indicia is for the purpose of illustrating unclaimed subject matter that forms no part of the claimed design.
